19 Claims. (Cl. 234—10)

This invention relates to a device for subsequent improvement of the justifiability of a line already punched, such apparatus being disposed on perforators for producing punched tapes for controlling matrix setting and line casting machines.

On setting machines having a manually operated keyboard, it is possible subsequently to insert $\frac{1}{4}$, $\frac{1}{2}$ or 1 em quads in a line already composed if it is found at the end of the line that the space quoins are not sufficient to justify the line. This occurs particularly when narrow formats are being set. In such a case the necessary em quad matrices are inserted after the space quoins.

Hitherto it has been difficult, particularly in the case of narrow formats, to punch tapes to control modern matrix setting and line casting machines. Known perforators for making such punched tapes are admittedly provided with an indicator system which adds up the numerical values according to the width of the inserted matrices and the minimum and maximum width of the space quoins and indicates the length of the part of the line that has been set, the remainder of the line still unused, and the justifiability of the space quoins inserted in the line (see U.S. patent specifications 2,059,250, 2,069,240, 2,080,424 and 2,083,570). However, if the indicated justifiability of the space quoins introduced was not sufficient to justify the completely punched line, the justifiability of the line could hitherto be improved only to a limited extent, a $\frac{1}{4}$ em quad perforation being punched over the space quoin perforation, and a space quoin and a $\frac{1}{4}$ em quad matrix being released by the resultant new combination of perforations in the automatic setting machine. Frequently, however, the additional $\frac{1}{4}$ em quad matrices are not sufficient, so that the incorrectly punched line has to be cancelled.

The cancelling operation is time-consuming. The line has to be punched a second time; the matrix setting and line casting machine controlled by the punched tape is stationary for the period during which the cancelled part of the punched tape passes through it.

Particularly in the composing of narrow formats, an attempt has hitherto been made to obviate this by operating the spacer key after each operation of the space quoin key in the perforator. The spacer key initiates transport of the punched tape by one step and the punching of a transport perforation. If the perforator operator discovered at the end of a punched line that the space quoins and additional $\frac{1}{4}$ em quad matrices were not sufficient to justify the line, he could manually turn the punched tape back and punch in a $\frac{1}{2}$ or 1 em quad perforation as necessary over the space provisionally provided after any space quoin perforations and thus improve the line justifiability.

The additional spaces on the punched tape do not interrupt operation of the controlled setting machine since the tape readers of the setting machine are so designed that they do not initiate any function during the reading of such a space.

Although, in many cases, the above-described method avoids cancellation of a full line, this method of correction is also liable to trouble. It requires a great degree of concentration on the part of the operator in re-

2

spect of the spacer key, so that his attention is diverted from reading the manuscript. Capacity and setting speed are reduced.

To obviate these disadvantages, the object of the invention is to provide an apparatus in perforators for producing punched tapes for controlling matrix setting and line casting machines, whereby the justifiability of a line already punched can be subsequently improved in similar manner.

5 To this end, according to the invention, there are provided between the space quoin key and the device normally operated by a separate tape transport key for punching a transport perforation and providing a space on the punched tape, a switch and mechanical and/or electrical transmission elements which, when the switch is closed, result in the punching of an additional transport perforation with a space on the punched tape in addition to the punching of a space quoin perforation on each operation of the space quoin key.

10 The advantage of this arrangement is, in particular, that the perforator operator with the device according to the invention can introduce a space on the punched tape only for the setting of narrow formats and without any diversion from the manuscript after each punching of a space quoin.

15 The introduction of the additional transport perforation in the punched tape can be effected simultaneously with the punching of the space quoin perforation if the perforator punching device is appropriately designed, but 20 preferably follows the punching of the space quoin perforation.

25 To enable additional em quad perforations to be subsequently made, the punched tape must be moved backwards. According to the invention it is particularly advantageous to provide the punched tape drive with a device for the stepwise return transport of the punched tape and to dispose the operating key for the key-operated return transport device contactor in the standard perforator keyboard.

30 With the new apparatus the perforator operator can initiate the punched tape return transport from the perforator keyboard without turning the punched tape back manually.

35 This apparatus can be complemented by providing an additional repetition key for operating the punched tape return transport device, such repetition key initiating a continuous return of the punched tape for the period of operation of such key.

40 Although this system gives an appreciable improvement to the stepwise return transport such as to render it automatic, the operation of the perforator can be rendered still more automatic by additionally providing a punched tape reader in the perforator, such reader being so adjusted that it stops the punched tape return transport device if a space quoin perforation combination occurs.

45 In fact, automatic operation is rendered possible if the punched tape return transport stop device is connected to a switching device which on each return transport stop automatically punches a pre-selected justification matrix over the space step and feeds its numerical value to the perforator indicator system adding device.

50 To enable the required em quad matrices to be selected more rapidly or to facilitate the decision as to whether $\frac{1}{4}$, $\frac{1}{2}$ or 1-em quads have to be inserted as justification matrices, an additional counter may be provided which on each operation of the space quoin key is advanced by one unit and is cleared to zero when the justification symbol is punched.

55 Further (full) automatic operation can be obtained if 70 a known electronic computer computes the width of any additional matrices required from the remainder of the line determined by the perforator indicator and not justi-

fiable without extra matrices and from the number of introduced space quoins determined by the aforesaid counter and initiates the tape transport and the subsequent punching for the extra matrices.

With the apparatus according to the invention the preparation of punched tapes for controlling matrix setting and line casting machines, particularly for the setting of narrow formats, can be greatly simplified. Time-consuming cancellation or correction are thus avoided and the same applies to any diversion of the operator's attention from the manuscript.

Further features, advantages and possible applications of the invention will be apparent from the following description of embodiments given by way of example with reference to the accompanying drawings, in which:

FIGURE 1 shows a first exemplified embodiment of the invention.

FIGURE 2, consisting of FIGURES 2a and 2b, shows a modified exemplified embodiment of the invention, and

FIGURE 3, consisting of FIGURES 3a and 3b, shows a further modified exemplified embodiment of the invention for fully automatic operation.

In the illustrations of all the exemplified embodiments like elements have been given like references. All the keys in the three exemplified embodiments are preferably situated in the standard perforator keyboard.

In the exemplified embodiment shown in FIGURE 1, an electric or electromagnetic connection constructed according to the invention is shown between a space quoins key 1 and a tape transport key 2 of the perforator. The space quoins key 1 normally initiates the punching of a space quoins combination on the punched tape with appropriate tape transport and the indication of the numerical values corresponding to the minimum and maximum width of the space quoins on a known perforator indicator. The tape transport key 2 normally initiates the punching of a transport perforation with corresponding tape transport. For the sake of clarity, these known normal functions of the keys have not been shown.

In order that each operation of the space quoins key may initiate not only the punching of a space quoins perforation combination on the punched tape and the delivery of space quoins numerical values to the indicator, but also, after the closure of a switch 3, a following punching of a transport perforation combined with a space on the punched tape for possible subsequent over-punching, a switch 1a is connected to the space quoins key 1 and is closed on each operation of the space quoins key. The movable contact of the switch 1a is connected to ground. From the switch 1a a lead 1b leads to the switch 3 and to an electromagnetic counter 8. The counter is also connected by a lead 8b and a common line 90 to the negative pole of a voltage source 91, whose positive pole is at ground potential.

The switch 3, which is operable in any desired manner, preferably by means of a key 3a on the standard perforator keyboard, connects a circuit comprising elements 4, 5, 6 and 7 to the line 1b when the switch 3 is closed. The circuit consists essentially of a crystal diode 6 connected in parallel with the relay winding, a condenser 5 connected in series with relay 4 and diode 6, and a resistor 7 connected in parallel with the series circuit comprising the relay winding 4, diode 6 and the condenser 5. The circuit is connected by its free end to the negative pole of the voltage source 91.

According to the invention, the tape transport key 2 is combined with an operating magnet 2b which operates the tape transport key when energised. One input 2c of the operating magnet 2b is connected by a working contact 4a of the relay 4 to ground, while the other magnet input is connected to the line 90.

A return magnet 8a is provided to return the counter 8 to the zero position and one of its inputs is connected to the line 90 while its other input is connected by a line 8c and a switch 9a operated by a key 9 to ground. The

key 9 is advantageously the perforator key normally used for punching the justification symbol. When it is operated, the switch 9a is closed so that voltage is applied to the return magnet 8a.

The circuit arrangement shown in FIGURE 1 operates as follows:

When the switch 3 is closed, the circuit arrangement 4, 5, 6 and 7 is connected to the line 1b. The switch 1a is closed on operation of the space quoins key 1. The counter 8 is thus advanced one step and ground potential is applied to the circuit 4, 5, 6 and 7. The condenser 5 is charged since a circuit is closed from ground, the contact 1a of the space quoins key, the switch 3, the condenser 5, the crystal diode 6 to the negative pole of the voltage source 91. The relay 4 is short-circuited by the crystal diode 6 and is therefore not actuated.

If the space quoins key 1 is released so that the switch 1a opens, the condenser 5 discharges through resistor 7 and the winding relay 4, the crystal diode 6 being non-conductive in this direction. The discharge current of the condenser 5 energizes relay 4. The working contact 4a of the relay 4 is closed so that the magnet 2b is energised and in turn actuates the tape transport key 2. The relay remains energised until the condenser 5 is discharged. That is sufficient to initiate the punching of a transport perforation on the punched tape with associated tape transport by means of the tape transport key. Since this operation takes place immediately after operation of the space quoins key 1, the space on the punched tape is situated immediately after the space quoins perforation.

At the end of the line punching operation the counter 8 shows the number of spaces on the tape provided as a precaution—such a number corresponding to the number of space quoins introduced. From this, and from determination of the remainder still to be filled from the perforator indicator, it is possible to estimate or calculate what size of fixed spaces in the form of $\frac{1}{4}$, $\frac{1}{2}$ or 1-em quads must be introduced for the remainder of the line to be distributed uniformly over the spaces between the words.

FIGURE 2 diagrammatically illustrates the circuit arrangement for another embodiment of the invention. The keys 1, 2 and 9 correspond in function to the keys bearing the same references in FIGURE 1, except that the key 2 co-operates with a switch 2a.

In addition, a repetition key 30 is provided with a switch 30a, a tape return key 28 with a switch 28a and a justification matrix key for each type of introducible fixed justification matrix, for example a key for each of the $\frac{1}{4}$, $\frac{1}{2}$ and 1-em quad matrices. Only one key 42 is shown of the justification matrix keys. The key 42 co-operates with a switch 42a. The circuit arrangement and operation of the other justification matrix keys correspond to the key 42. The movable contacts of switches 1a, 2a, 9a, 28a and 42a are connected to ground.

The punched tape is perforated in known manner by punches (not shown) pre-selected or operated directly by code punching magnets.

Three recording means in the form of code punching magnets—magnets 20, 35 and 38—are shown in FIGURE 2. The magnet 38 symbolically represents the other code punching magnets, the total number of which corresponds to the number of code punching lines used, for example six lines to a six-digit code. For the sake of simplicity it will be assumed that the perforation punched in the punched tape on operation of the magnet 20 corresponds to the combination of perforations for one space quoins, and the perforation punched on operation of the magnet 35 corresponds to the combination of perforations for a given justification matrix, for example a $\frac{1}{4}$ em quad justification matrix. For punching the perforation combinations of other justification matrices, for example $\frac{1}{2}$ and 1-em quad matrices, and for punching the letters, other combinations of code punching magnets are oper-

ated, if desired with the interposition of a known coding matrix. A magnet 23 is provided for initiating the transport perforation. Any amplifiers required before the magnets have been omitted for the sake of simplicity.

The tape transport by means of the perforator is effected by a drive motor 26, for example a stepping motor, the direction of rotation of which can be reversed by change-over switches 29a and 29b by reversing the polarity of the field winding 26a. Instead of a reversible field winding other means may be used to reverse the direction of transport of the punched tape, for example a reversing gear. The change-over switches 29a and 29b are relay contacts of a relay 29, whose winding is connected to the switch 28a of the tape return key 28 and the common line 90 leading to the negative pole of the battery 91.

As in the arrangement shown in FIGURE 1, the switch 1a of the space quoins key 1 is connected to the counter 8, and the switch 9a of the justification symbol key 9 is connected to the counter return magnet 8a. Counter 8 and return magnet 8a are also connected to the common line 90. By way of line 1b the space quoins key 1 can also act on a bi-stable switching element 18, the re-setting input of which is connected by a line 18a to a complementary output of a mono-stable switching element 25. The output of the bi-stable switching element 18 is taken via line 18b to an input of the numerical value adding mechanism 15 of the perforator indicator system, an OR-circuit 21 and one input of an AND-circuit 19. The complementary output of the bi-stable switching element 18 is connected via the switch 3 to a second input of the OR-circuit 21, which input is connected to the switch 2a of the tape transport key 2. A third input of the OR-circuit 21 is connected to the switch 42a of the justification matrix key 42. The output of the OR-circuit 21 is connected to the input of another mono-stable switching element 22. The output of the element 22 is taken via a normally closed contact 29c of the relay 29 and a line 22a to one input of each of the AND-circuits 19 and 34 and the transport perforation magnet 23. A second input of the AND-circuit 34 is connected to the switch 42a of the justification matrix key 42 and is connected via the line 33a to the adding mechanism 15.

A complementary output of the mono-stable switching element 22 is connected to one normally open contact 29d of the relay 29 in series with the switch 30a of the repetition key 30 and by a delay network 24 to the input of the mono-stable switching element 25. The output of the element 25 leads to the changeover switches 29a and 29b of the field winding 26a of the transport motor 26.

The outputs of the AND-circuits 19 and 34 are connected to one side of the magnet windings 20 and 35, whose other sides like those of the magnet 23 are connected to the common line 90. Thus switch 30a is connected to the re-setting input of the bi-stable switching element 18.

By means of a changeover contact 29e of the relay 29 the adding mechanism 15 of the perforator indicator system is set to forward or reverse counting. An example of a reversible adding mechanism of this kind is disclosed in U.S. Patent No. 3,083,897. A re-setting input of the adding mechanism 15 is connected to the switch 9a of the key 9.

The arrangement operates as follows:

On operation of the space quoins key 1 the switch 1a is closed, and advances the space quoins counter 8 by one step to indicate the total number of space quoins introduced into a line, and sets the bi-stable element 18. By way of the element 18, counting information corresponding to the space quoins width is fed to the adding mechanism 15 and a pulse passes to the AND-gate 19. The mono-stable element 22 is also switched over by way of the OR-gate 21 and thus in turn passes information by the closed contact 29c to the other input of the AND-gate 19 so that the AND-gate is opened and the punch-

ing magnet is released to punch the space quoins combination. At the same time the magnet 23 for punching the transport perforation is also released.

After a certain time determined by the circuit elements of the mono-stable switching element 22, the element 22 swings back to its initial state so that no current is applied to the magnets 20 and 23. The complementary output of the mono-stable switching element 22 passes a pulse through the delay network 24 to the mono-stable element 25 which in turn applies current to the transport motor 26 for one transport step. During the delay period produced by the delay network 24, the punches can be withdrawn from the punched tape, for example by return springs.

On the switching back of the mono-stable element 25, its complementary output feeds a pulse to the re-setting input of the bi-stable element 18, so that this element returns to its position of rest.

If the switch 3 is closed so that the circuit is prepared for operation of the space quoins key followed by automatic tape transport, the complementary output of the bi-stable element 18 feeds another pulse via the OR-gate 21 to the mono-stable element 22, whereupon the transport perforation punching magnet 23 is operated a second time by an impulse transmitted by the closed contact 29c. In these conditions the magnet 20 does not produce a space quoins perforation, however, since the associated AND-gate 19 remains closed owing to the absence of information from the element 18. The rest of the program is as described above.

The adding mechanism 15 not only adds in known manner the values for the space quoins, but also the values of all the introduced matrices. If the perforator operator then finds at the end of a line that too many letters have been introduced, the punched tape transport mechanism can be returned by the corresponding number of steps and the value of the associated matrices can be subtracted in the adding mechanism 15, the tape return key 28 and the letter keys corresponding to the excessive number of matrices being operated simultaneously. This takes place as follows:

The tape transport key 2 or the letter keys (not shown) connected in the same way as the tape transport key, feed a pulse, via the switch 2a and the OR-gate 21, on each transport step to the mono-stable element 22, which when it returns to its inoperative state passes the pulse on, as described above, to the mono-stable element 25. The relay 29 is energised via the contact 28a of the tape return key 28 and reverses the transport motor 26 via the relay contacts 29a and 29b by reversing the polarity of the field winding 26a, and the motor runs in the opposite direction, that is, for return transport. On each swing-over of the mono-stable element 25 a reverse transport step is therefore performed so that on the reverse keying of the last word in the particular line the punched tape again stops in its position in front of this word. The changeover contact 29e of the relay 29 switches the adding mechanism 15 to subtraction during the return keying operation so that on actuation of the required letter keys the counted values of the reversed matrices are deducted. The normally closed contact 29c of the relay 29 opens and prevents the code punching magnets 20, 35, 38 and the transport punching magnet 23 from being operated during the reverse keying operation.

After the reverse keying operation the excessive word is cancelled by over-punching in the perforation station.

If after completion of this operation it is found by reference to the indicator comprising the adding mechanism 15 that the justification range of the space quoins is not sufficient to fill the line in this form, $\frac{1}{4}$, $\frac{1}{2}$ or $\frac{3}{4}$ em quad matrices must be subsequently introduced in addition to the space quoins perforations. It is easy to determine which of these fixed justification matrices is adapted to dividing the remainder of the line over the spaces between the words, by dividing the line remainder

value shown on the indicator by the number of introduced space quoins indicated by the counter 8.

For the subsequent insertion of the justification matrices the punched tape must be returned again, this being done manually or by simultaneous operation of keys 2, 28 and 30. By means of its contact 2a the key 2 passes a pulse via the OR-gate 21 to the mono-stable element 22 whereupon, as described above, a return transport step takes place while any perforation is prevented by the open contact 29c of relay 29.

On the swinging back of the mono-stable element 25, its complementary output passes a pulse through the closed switch 30a of the key 30, the closed contact 29d of the relay 29 and the delay network 24, to its own input, whereupon the element 25 again swings over and produces a further return step of the punched tape transport motor 26. The return transport continues until the key 30 is released and the key contact 30a opened. The key is advantageously released when the tape transport perforation after the space quoin perforation is situated above the punches. The keys 2 and 28 are also released, the relay 29 drops.

By operation of the appropriate justification matrix key the perforation combination for the required justification matrix can now be introduced into the punched tape instead of the space after the space quoin perforation combination. If, for example, the key 42 is operated for this purpose, a pulse passes the OR-gate 21, the mono-stable element 22 and the closed contact 29c to one input of the AND-gate 34 while the other input of the AND-gate is controlled directly by the switch 42a. The AND-gate 34 thus conducts and passes current to the magnet 35 of the appropriate justification matrix perforation combination. The counted value of the subsequently introduced justification matrix is simultaneously determined in the adding mechanism 15 of the perforator indicator system so that after completion of the subsequent insertion the justifiability of the line can be checked. Repeated forward transport of the punched tape can be produced in accordance with the above by operation of the keys 2 and 30, the other justification matrix perforations being made in the same way as described above. At the end of the line the key 9 is depressed to punch the justification symbol and at the same time the counter 8 and the adding mechanism 15 are re-set by means of the magnet 8a.

The arrangement shown in FIGURE 3 corresponds extensively to that shown in FIGURE 2 in respect of its construction but has been extended in comparison therewith so that improvement of the justifiability of the line can be performed fully automatically.

A computer 37 is provided to evaluate the values at the end of punching a line for the nonjustifiable remainder of the line (adding mechanism 15) and for the total number of introduced space quoins (indicated at the counter 8).

To the computer there leads a line 9b from the contact 9a of the key 9 for the line end symbol, a line 1b from the contact 1a of the space quoin key 1 and a line 15a from the output of the adding mechanism 15. The computer 37 is connected to ground by a normally open contact 41d of a relay 41. The output of the computer 37 is connected by the line 37a to the input of a justification matrix selector 33—for example an electrically controllable stepping mechanism, a relay network or an equivalent electronic arrangement—which is connected to earth by the normally open contact 32b of a relay 32. One output of the selector 33 is connected to the input of the AND-gate 34 in front of the code punching magnet 35. Further outputs of the selector are connected (in manner not shown) to the AND-gates of other code punching magnets or of combinations of such magnets. Each output of the selector is associated with a particular justification matrix, for example $\frac{1}{4}$ -em, $\frac{1}{2}$ or 1-em quads.

A sensing system 31 is provided in front of the perforator punching station (not shown) and senses the perforation of the punched tape 50 and its identification elements are preferably situated one transport step in front of the punches. Reference 17 on the punched tape denotes a transport perforation and reference 16 denotes, for example, a combination of space quoin perforations.

The sensing mechanism 31 has three outputs a, b, c. At the output a a signal occurs if there is a combination of space quoin perforations, and at the output b a signal occurs if there are line end symbols present, while at the output c there are signals as long as the identification elements encounter any combinations of perforations in punched tape 40. Between the output a of the sensing device 31 and the common line 90 there are connected in series the relay 32 and the normally open contacts 36a and 40d of the relays 36 and 40 respectively. The relay 40 is connected to the output b of the sensing system 31 and the common line 90. The output c of the sensing system 31 is connected by a normally open contact 40b of the relay 40 to the output b.

The relay 36 is constructed as a delay relay and is disposed between the common line 90 and the line 22a. In parallel with the normally closed contact 29c of the relay 29 is a normally open contact 32d of the relay 32. By way of a normally open contact 41c of the relay 41, the relay 29 can be connected to earth independently of the tape return key. The relay 41 is connected to the common line 90 and by a key switch 45 to ground. In parallel with the switch 45 there are connected in series a normally closed contact 40c of the relay 40 and a normally open contact 41b of the relay 41.

Connected in parallel with the switch 30a of the repetition key 30 are other normally open contacts 41a and 40a of the relays 41 and 40 respectively. The contact 29d of the relay 29 is constructed as a changeover contact, contrary to FIGURE 2. A changeover contact 32a of the relay 32 is disposed between the switch 30a and the changeover contact 29d. One input of the OR-gate 21 is connected to the changeover contacts 29d and 32a.

The key 42 provided in the system shown in FIGURE 2 is eliminated. Its function is performed by the selector 33.

Otherwise the circuits according to FIGURES 2 and 3 correspond.

The operation of the system shown in FIGURE 3 corresponds exactly to that shown in FIGURE 2 in respect of punching of the line, punched tape return transport in the event of an excessive number of letters being introduced, and over-punching of the excessive word or part of a word, so that it is not necessary to discuss these operations again.

If, after a line has been punched and any excessive letters have been cancelled by over-punching, it is found that justification matrices must be subsequently introduced to enable the line to be justified, the operator presses the key 45 so that the relay 41 pulls up and holds itself by its normally open contact 41b and normally closed contact 40c. Closure of the contact 41d operates the computer 37 which divides the line remainder value by the number of introduced space quoins and determines the most suitable type of justification matrix for justifying the line. Corresponding information is fed from the output of the computer and line 37a to the justification matrix selector 33, which is thus set to the appropriate type of justification matrix, for example $\frac{1}{4}$ -em justification matrices.

The circuit of the relay 29 is closed by the closed contact 40a by the contact 41c, and the relay 29 pulls up. The contacts 29a and 29b reverse the polarity of the field winding 26a of the transport motor 26 to reverse transport. The changeover contact 29d, the contact 32a and the closed contact 41a connect the complementary output

of the mono-stable element 25 to the input of the delay network 24.

If the tape transport key 2 is then pressed and the switch 2a closed, a pulse passes through the OR-gate 21 to the mono-stable element 22. Undesired punching as a result of the changeover of the element 22 is prevented since the contact 29c is opened. The complementary output of the element 22 feeds a pulse to the delay network 24 and to the mono-stable element 25 so that from the output of the element 25 the motor 26 receives current for a reverse transport step. On the switch back the element 25 feeds a pulse via the contacts 41a, 32a and 29d and the delay element 24 to its own input so that it swings again and initiates another reverse step of the transport motor 26.

Return transport continues until a combination of space quoins combinations 16 comes beneath the identification elements of the sensing system 31 and consequently there appears at the output a of the sensing system a signal which actuates the relay 32 by means of contacts 36a and 40d. The changeover contact 32a breaks the connection between the complementary output of the mono-stable element 25 and the input of the delay network 24, and the punched tape 50 stops. The pulse occurring at the complementary output of the element 25 when it switches back is fed by the contacts 41a and 32a to the OR-gate 21 and then to the input of the mono-stable element 22. The element 22 switches over and its output feeds a pulse through the closed contact 32d to the input of the AND-gate 34. The other input of the AND-gate is controlled by the matrix selector 33 by the closure of the contact 32b.

The AND-gate 34 thus conducts and feeds current to the code punching magnet 35. The code perforation combination for the justification matrix determined by the computer 37 and selected at the selector 33 is punched in the tape 0 at the blank space after the space quoins combination. The numerical value of the selected subsequently inserted justification matrix is simultaneously detected in the adding mechanism 15 so that the justifiability of the line can be checked after the completion of the subsequent insertion process. The pulse delivered by the output of the mono-stable element 22 causes the relay 36 to be energized with a delay so that the contact 36a is opened and the relay 32 drops. The changeover contact 32a makes the connection from the complementary output of the mono-stable element 25 to the input of the delay circuit 24 again and when the mono-stable element 22 swings back the element 25 swings by way of the delay network 24. Contacts 32b and 32d have opened. The punched tape runs back further, the relay 36 dropping again. As soon as the sensing system 31 finds another combination of space quoins perforations, the above-described operation is repeated.

This takes place until the sensing system 31 finds the line end symbol of the preceding line on the punched tape 50 and energises the relay 40 via its output b. The relay 40 actuates the contact 40c and causes the relay 41 to drop, which in turn does the same to the relay 29 by the contact 41c. The contacts 29a and 29b change the transport motor 26 over to forward. By means of the contact 40a of the relay 40 to complementary output of the mono-stable element 25 is connected by the contacts 32a and 29d and the OR-gate 21 to the input of the mono-stable element 22 so that the forward transport continues to operate. During forward transport the relay 40 holds itself by its contact 40b for as long as the sensing system 31 finds punch code combinations on the punched tape and by opening of the contact 40d prevents the relay 32 from pulling up again when the space quoins perforation combinations pass the sensing system 31. The relay 40 drops as soon as the end of the last line punched is reached, and by the opening of its contact 40a stops the repeated forward transport.

By means of the key 9 it is now possible (in conventional manner not illustrated) to punch the justification

symbol. At the same time, the counter 8, the adding mechanism 15 and the computer 37 are re-set. The circuit arrangement is restored to its original state.

It is self-evident that the invention is not limited to the use of punched tapes, but can be correspondingly used for recording on other record carrier and for any code element combinations for representing the individual recording in a code.

It is also possible to provide numerous intermediate modifications between the manually operated embodiments according to FIGURE 2 and the fully automatic embodiment according to FIGURE 3.

I claim:

1. An apparatus for recording the program of a line casting machine, comprising, in combination, manually operated means for recording on a record carrier a recording representing a space quoins; a device for providing on said record carrier a blank space; and means for connecting said manually operated means with said device to actuate the same upon operating of said manually operated means so that a blank space adapted to receive a recording representing a justifying em quad or fraction thereof is provided on said record carrier adjacent each recording representing a space quoins.

2. An apparatus for recording the program of a line casting machine, comprising, in combination, manually operated means for recording on a record carrier a recording representing a space quoins; a device for providing on said record carrier a transport perforation and a blank space; and means for connecting said manually operated means with said device to actuate the same upon operating of said manually operated means so that a blank space adapted to receive a recording representing a justifying em quad or fraction thereof is provided on said record carrier directly following each recording representing a space quoins.

3. An apparatus for recording the program of a line casting machine, comprising, in combination, manually operated means for recording on a record carrier a recording representing a space quoins; a device for providing on said record carrier a blank space; and circuit means including a switch operated by said manually operated means for connecting said manually operated means with said device to actuate the same upon operating of said manually operated means so that a blank space adapted to receive a recording representing a justifying em quad or fraction thereof is provided on said record carrier adjacent each recording representing a space quoins.

4. An apparatus for recording the program of a line casting machine, comprising, in combination, manually operated means for recording on a record carrier a recording representing a space quoins; a device for providing on said record carrier a blank space; and circuit means including a switch operated by said manually operated means for connecting said manually operated means with said device to actuate the same upon operating of said manually operated means so that a blank space adapted to receive a recording representing a justifying em quad or fraction thereof is provided on said record carrier adjacent each recording representing a space quoins, said circuit means including means for causing actuation of said device a selected time after actuation of said manually operated means.

5. An apparatus for recording the program of a line casting machine, comprising, in combination, manually operated means for recording on a record carrier a recording representing a space quoins and for causing movement of said record carrier in a recording direction; a device for providing on said record carrier a blank space; means for connecting said manually operated means with said device to actuate the same upon operation of said manually operated means so that a blank space adapted to receive a recording representing a justifying em quad or fraction thereof is provided on said record carrier adjacent each recording representing a space quoins; returning

means for moving said record carrier in a return direction opposite to said recording direction; sensing means for sensing recordings representing a space quoins during movement of said record carrier in said return direction; and a stop device controlled by said sensing means to stop said returning means and thereby said record carrier when a recording representing a space quoins is sensed.

6. An apparatus for recording the program of a line casting machine, comprising, in combination, manually operated means for recording on a record carrier a recording representing a space quoins and for causing movement of said record carrier in a recording direction; a device for providing on said record carrier a blank space; means for connecting said manually operated means with said device to actuate the same upon operating of said manually operated means so that a blank space is provided on said record carrier adjacent each recording representing a space quoins; returning means for moving said record carrier in a return direction opposite to said recording direction; sensing means for sensing recordings representing a space quoins during movement of said record carrier in said return direction; a stop device controlled by said sensing means to stop said returning means and thereby said record carrier when a recording representing a space quoins is sensed; and means controlled by said sensing means and said stop device to effect a recording representing an em quad or a fraction thereof in each blank space.

7. An apparatus as set forth in claim 6 and including counter means for counting a numerical value correlated with the em quad or fraction thereof recorded in each said blank space, said counter means being adapted to be connected to an indicator so that the justifiability of a line can be determined.

8. An apparatus for recording the program of a line casting machine, comprising, in combination, manually operated means for recording on a record carrier a recording representing a space quoins; a device for providing on said record carrier a blank space; means for connecting said manually operated means with said device to actuate the same upon operating of said manually operated means so that a blank space is provided on said record carrier adjacent each recording representing a space quoins; means for recording in said blank spaces recordings representing a justifying em quad or fraction thereof; counting means for counting the number of actuations of said manually operated means and having clearing means; means for recording on said record carrier a justification symbol at the end of a line and controlling said clearing means to clear said counter means upon recording of a justification symbol.

9. Apparatus for controlling the tape perforator of a line casting machine, comprising, in combination, a space quoins key for operating said perforator to punch a space quoins perforation; a device for punching a transport perforation and for providing a blank space on a tape; and circuit means including a switch operated by said space quoins key for connecting said space quoins key with said device to actuate the same upon operation of said space quoins key to punch a transport perforation and to provide a blank space on the tape adjacent the space quoins perforation punched under the control of said space quoins key.

10. Apparatus for controlling the tape perforator of a line casting machine, comprising, in combination, a space

quoins key for operating said perforator to punch a space quoins perforation; a device for punching a transport perforation and for providing a blank space on a tape; a tape transport key for normally operating said device; and circuit means including a switch operated by said space quoins key for connecting said space quoins key with said device to actuate the same upon operation of said space quoins key to punch a transport perforation and to provide a blank space on the tape adjacent the space quoins perforation punched under the control of said space quoins key and independently of said tape transport key.

11. An apparatus as set forth in claim 10 wherein said circuit includes means for causing actuation of said device a selected time after actuation of said space quoins key.

12. An apparatus as set forth in claim 10 including drive means for said tape and including means for forward transport and means for return transport of said tape; and a control key for controlling said last mentioned means, said control key and said space quoins key being located in the region of a key board which is adapted for the standard operation keys of the perforator.

13. An apparatus as set forth in claim 12 wherein said key board includes an additional repetition key connected to said drive means for causing continuous movement of said tape in said return direction during actuation of said repetition key.

14. An apparatus as set forth in claim 12 including a punched tape reader; and a stop device controlled by said tape reader and controlling said drive means to stop movement of the tape in said return direction when said tape reader senses a space quoins perforation.

15. An apparatus as set forth in claim 14 including a switching device controlled by said stop device; and punching means controlled by said switching device upon stopping of said tape to punch in said blank space a perforation representing a preselected justification matrix.

16. An apparatus as set forth in claim 15 and including an indicator for indicating numerical values correlated with perforations made in said tape; and means controlled by said switching device to supply a signal representing the numerical values of said preselected justification matrices to said indicator.

17. An apparatus as set forth in claim 10 and including a counter controlled by said space quoins key to count the actuations of the same; and means for punching at the end of a line a justification symbol into said tape and connected to said counter for clearing the same.

18. An apparatus as set forth in claim 10 including an electronic computer for determining justifiability of lines whose matrices are represented by perforations in said tape; and means controlled by said computer for indicating whether $\frac{1}{4}$, $\frac{1}{2}$ or 1 em quads are to be represented by recordings in said blank spaces.

19. An apparatus as set forth in claim 18 and including a justification matrix selector controlled by said computer.
